UNITED STATES PATENT OFFICE.

ERNST G. K. ANDERSON, OF CHICAGO, ILLINOIS, ASSIGNOR, BY MESNE ASSIGNMENTS,
TO APPLETON ELECTRIC CO., OF CHICAGO, ILLINOIS, A CORPORATION OF ILLINOIS.

REEL STRUCTURE FOR EXTENSION CORDS.

Application filed August 14, 1919. Serial No. 317,398.

To all whom it may concern:

Be it known that I, ERNST G. K. ANDERSON, a citizen of the United States, and a resident of Chicago, in the county of Cook 5 and State of Illinois, have invented certain new and useful Improvements in Reel Structures for Extension Cords; and I do hereby declare that the following is a full, clear, and exact description thereof, reference being had to the accompanying drawings, and 10 to the characters of reference marked thereon, which form a part of this specification.

This invention relates to improvements in spring rewinding reels for cords, cables, and 15 the like, of that type having locking means to lock the reel after a desired length of cord has been unwound therefrom, the locking means being constructed to be released by sharp pull of the cord which sets in motion 20 the rewinding mechanism to rewind the cord on the reel.

Among the objects of the invention is to provide an exceedingly simple and economical rewinding reel in which the rewinding 25 springs are arranged to produce a substantially sustained rewinding pull on the cord or cable, regardless of the length of the cord unwound from the reel, to provide a construction which is compact relatively to its 30 cord receiving capacity, to provide a construction in which the principal elements may be made of simple stamped metal parts and which may be readily assembled by unskilled labor and parts of which may be fastened together without the use of separate 35 fastening means, as rivets, to otherwise improve and simplify rewinding reels of this general character.

The invention consists in the combination 40 and arrangement of the parts shown in the drawings and described in the specification and is pointed out in the appended claims.

In said drawings,

Figure 1 is a side elevation of a rewinding 45 reel embodying my invention.

Figure 2 is an end view thereof.

Figure 3 is an enlarged axial section of the reel drum and the actuating springs and associated mechanism.

50 Figures 4 and 5 are detail sections on lines 4—4 and 5—5, respectively, of Figure 3.

Figure 6 is a detail section on the line 6—6 of Figure 2.

55 Figures 7 and 8 are detail views of the plural-part winding drum.

As shown in said drawings, 10 designates as a whole the reel spool on which a cable or cord 11 is adapted to be wound. 12, 12 designate the cord confining flanges of the spool.

13, 13' designate the rewinding springs 60 which are placed under tension as the cord is reeled off the spool and which by expansion rotate the spool to wind the cord thereon, and 14 designates a fixed shaft about 65 which the reel rotates.

The said reel is made of a plurality of members 15, and preferably two as herein shown. (See Figures 7 and 8.) It is convenient and practicable to make the two spool members 15 of sheet metal and of identical shape and size so as to produce them by the operation of a single set of dies. Each spool part is formed with an exterior concave bay so arranged that when the spool parts are assembled an annular support for 70 the cord is formed which is concave in longitudinal section. The said spool parts are provided at their ends with endwise extended lugs 16, two adjacent lugs at each end thereof and at diametrically opposed sides 75 of the axis of the spool being mating lugs.

The springs 13, 13' are enclosed in spring barrels 17, located one at each end of the spool. Each barrel comprises a cylindric wall 18 concentric to the axis of the shaft 14 85 and an end wall 19 transverse to said axis. Preferably and as herein shown, the limiting flanges 12 of the spool form integral parts of the cylindric walls 18 of the spring barrels.

The barrel 17 which contains a spring 13 90 is closed at its inner end by a spring retaining plate or disc 20 which is fitted over the cylindric portion of the shaft 14 and is provided with a marginal, outwardly turned cylindric flange 21 which fits and turns within 95 the cylindric rim 18 of the barrel and is adapted to be fixedly secured to one end of the spring 13 by a rivet or like fastening device 21'. The other or inner end of said spring is fixed, as by means of a pin 22, to 100 the shaft 14. The barrel 17 which contains the spring 13' is closed at its inner end by a circular spring retaining plate or disc 23 which fits at its margins between the associated outstanding limiting flange 12 and 105 the end of the spool. One end of said spring 13' is fixed, as by means of a rivet 24, to the annular rim 18 of the associated barrel 17, and the other or inner end of the spring is fixed, as by means of a pin 25 (Fig. 5), to 110

the adjacent end of a sleeve 26 that is loosely mounted on the shaft 14; the other end of said sleeve being soldered or otherwise rigidly fixed to the spring retaining disc 20.

- 5 As herein shown, the parts of the reel structure thus far described are held in assembled relation by providing the cord limiting flanges 12 with angularly spaced openings 26 through which are adapted to extend 10 the lugs 16 on the multi-part spool; the said lugs being clinched down over the outer faces of the limiting flanges 12.

Fitted to the outer ends 19 of the spring barrels are cups 27 which, as best shown in 15 Figures 2 and 4, are held in place by means of lugs 28 that are formed integral with and extend laterally from the end walls of the barrels and extend beyond the flanges 29 of said cups and are clinched over insulating 20 discs 41 that externally overlie said cups, as shown in Figures 3 and 4, for a purpose hereafter described. Contained in the space enclosed by one of said cups are a plurality of 25 dogs 30 (Figures 3 and 4) which are pivoted at their ends to studs 31 that are struck up from the end wall of the spring barrel. Said dogs are provided at their other ends with teeth 32 that are adapted to engage in 30 recesses 33 which are formed on the periphery of a disc 34 that is fitted non-rotatively to the adjacent end of the shaft 14. As herein shown and preferably, said latter end of the shaft is flattened or squared at 35 and the collar 34 is provided with a like-shaped 35 opening to fit therein to hold the collar fixed on the shaft. The teeth of said dogs drop into the recesses of the collar to hold the reel from rewinding in a known manner but may be dislodged by a slight pull on the cord to 40 release the dogs to permit the rewinding of the cord on the spool.

The said reel may be supported in any suitable manner, as by means of arms 36, 37 which may be either depending, as hangers, 45 or upstanding, as shown. One of the supports is interlocked to the squared or flattened end of the shaft to hold the said shaft from turning with respect to said supports, but the spring barrels, the spool and the 50 sleeve 26 are allowed to freely turn in the shaft when the cord is withdrawn from or wound on the spool.

It will be noted that the spring barrels 17 and the cups 27 are of identical form and 55 construction, capable of being made by the use of the same set of dies. It will be furthermore observed, from an inspection of Figure 3, that the dogs are confined on their pivot lugs 31 by the enclosing cup 27 at the 60 end of the reel (either end as desired) so that it thereby becomes unnecessary to rivet said lugs over the dogs. This contributes to the ease in assembling the parts and also decreases the cost of the assembling operation.

65 The arrangement shown, wherein the

spring barrels are located at the ends of the spool and exterior thereto, permit the springs to be made of ample length to provide for withdrawal of a long length of cord, and also enables the spool to take the form 70 shown in Figures 1 and 3, to thereby increase the cord capacity of the spool.

The rewinding reel herein shown is adapted to receive a conductor cord through which electric current, from an external source, is 75 passed to an electrical device, as a machine, lamp, or the like. When the reel is thus adapted, suitable electrical connections are provided for the conductors 38 of the cord to conductors from an external source. The 80 circuit carrying members shown are made as follows:

40, 40 designate contact plates which lie outside of the cups 27 and are insulated therefrom by the discs 41. Said contact plates and insulated discs, as well also as the ends of the cups, are axially apertured for the passage of the shaft 14. The discs 41 referred to, and attached to the cups by the lugs 28, serve to insulate the contact plates 40 from the cups 27. Said contact plates are fastened in place by means of lugs 42 springing therefrom and extending into openings in projections 43 of the insulating discs 41 beyond the cups 27 and by arms 44 diametrically disposed relatively to said lugs 42 and which lie over insulating extensions 45 of the discs 41 and are bent downwardly at their terminals 46 to engage short insulating strips 47 that lie outside of the limiting 95 flanges 12 of the reel. The said arms 46, the cord limiting flanges 12, and the interposed insulating members 47 are provided with registering apertures to receive metallic bushings 48 which are in electrical contact 100 with said conductors and the contact disc arm 44 carry current from the conductors to the contact plates 40. The said terminal bushings 48 extend through and are riveted over the inner faces of insulating members 110 49 that are inset in recesses on the inner faces of the cord limiting flanges 12, as shown in Figure 6, the openings in said flanges being of a diameter to space the flanges from said bushings. The sheathed 115 portions of the conductors 38 are turned directly outwardly through other bushings which extend through other registering openings in the insulating member 47 and 49 and the cord limiting disc 12 so as to prevent objectional pulling stresses being brought on the connections of the conductors and terminal bushings 48 when the cord is wholly unreeled from the spool.

The external circuit may be closed to the 125 discs 40 through stationary wipers 51 that bear on the outer faces of said discs and are connected to binding posts 52, as shown in Figure 1.

In operation, the withdrawal of the cord 130

11 is resisted by both springs 13, 13', one of which is attached to the fixed shaft 14 and the other to the sleeve 26. Therefore, the rewinding springs act in series and exert a rewinding tension on the cord which is substantially uniform throughout the ranges of said cord.

I claim as my invention:

1. A rewinding reel comprising a spool, 10 spring barrels outwardly beyond the ends thereof, a fixed shaft extending through said barrels and said spool, and rewinding springs in said barrels connected to the shaft and one of the barrels and to each 15 other to operate in series to effect a substantially uniform rewinding tension on a cord wound on the reel.

2. A rewinding reel comprising a spool, 20 spring barrels outwardly beyond the ends thereof, a non-rotative shaft extending axially through the spool and said barrels, rewinding springs in the barrels, and a sleeve rotative on said shaft, one of said springs being connected at one end to said shaft 25 and at its other end to one end of said sleeve, and the other spring being attached at one end to one of the barrels and at its other end to said sleeve.

3. A rewinding reel comprising a spool, 30 spring barrels at the ends thereof, a non-rotative shaft extending axially through said spool and spring barrels, rewinding springs within said barrels, a spring retaining member at the inner side of one of said 35 barrels and provided with a cylindric flange fitted to the latter barrel, a sleeve rotative on said shaft and attached at one end to said spring retaining member and extending at the other end into the other barrel, one 40 of the springs being connected to said flange and to said shaft, and the other spring being connected to its associated spring barrel and to said sleeve.

4. A rewinding reel comprising a spool, 45 spring barrels at the ends thereof, a non-rotative shaft extending axially through the spool and said barrels, a sleeve rotative on said shaft, rewinding springs in the barrels, one of said springs being connected at one 50 end to said shaft and at its other to one end of said sleeve, and the other spring being attached at one end to one of the barrels and at its other end to said sleeve, a notched collar attached to said shaft, and gravity 55 dogs hinged to one of said barrels for cooperation with said notched collar.

5. In a rewinding reel structure, a spool, 60 a spring barrels fixed thereto, a rewinding spring in said barrel, a non-rotative shaft extending through said spool and barrel, a sleeve rotatable on said shaft to which the inner end of said spring is attached, the outer end of the spring being attached to said barrel, a notched collar non-rotatively 65 fixed to said shaft exterior to said barrel,

gravity dogs pivoted to the end of the barrel and co-operating with said collar, and a cup member fitted over the barrel end for retaining said dogs on their pivots.

6. A rewinding reel comprising a spool, 70 spring barrels at the ends thereof, a non-rotative shaft extending axially through the spool and said barrels, rewinding springs in said barrels, a sleeve rotative on said shaft, one of said springs being connected 75 to said shaft and to one end of said sleeve, and the other spring being attached to one of the barrels to said sleeve, one of the spring barrels being provided with integral lugs, gravity dogs pivoted to said lugs, a 80 notched collar non-rotatively fixed to the shaft adjacent said dogs, and a cup fitted to the latter spring barrel to retain said dogs on their pivots.

7. A rewinding reel structure comprising 85 a spool having end lugs, spring barrels at the ends thereof provided with radial flanges constituting cord retaining flanges and apertured to receive said lugs whereby the spring barrels are attached to the spool, 90 and rewinding springs in said barrels.

8. A rewinding reel comprising a spool having an exterior, longitudinally concave cord receiving space, a spring barrel at the end of the spool provided with a radial 95 flange, interlocking connections between said spool and said flange, and a rewinding spring in said barrel.

9. A rewinding reel structure comprising 100 a multi-part spool having end lugs, spring 105 barrels at the ends thereof provided with radial flanges constituting cord retaining flanges and apertured to receive said lugs whereby the spring barrels are attached to the spool and the spool parts are fixed to 105 each other, and rewinding springs in said barrels.

10. A rewinding reel structure comprising 110 a multi-part spool having end lugs, spring barrels at the ends thereof provided with 115 radial flanges constituting cord retaining flanges and apertured to receive said lugs, whereby the spring barrels are attached to the spool, and the spool parts are fixed together, and rewinding springs in said barrels, said spool being longitudinally concave.

11. A rewinding reel comprising a spool, 120 spring barrels at the ends thereof, a non-rotative shaft extending through said barrels and said spool, and rewinding springs in said barrels connected to the shaft and to one of the barrels and to each other to operate in series to effect a substantially 125 uniform rewinding tension on a cord wound on the reel, said spool being made of a plurality of identical parts provided at their ends with attaching lugs, and the barrels being provided with radial lugs constituting cord retaining flanges for the spool, 130

and provided with apertures to receive the retaining lugs of the spool.

12. A rewinding reel comprising a spool, spring barrels outwardly beyond the ends thereof to contain rewinding springs, said barrels having flanges to constitute cord limiting flanges, and the spool having endwise extending lugs to pierce said flanges and bent thereover to hold the spool and flanges together as a unitary structure.

13. A rewinding reel comprising a spool, spring barrels outwardly beyond the ends thereof to contain rewinding springs, said

barrels having flanges which constitute cord limiting flanges of the spool, the spool ends 15 being interlocked to the said flanges adjacent to the peripheries of the latter, and the spool being longitudinally concave between the flanges to increase the depth of the cord receiving space.

In testimony whereof I claim the foregoing as my invention, I hereunto append my signature at Chicago, Illinois, this 12th day of August, 1919.

ERNST G. K. ANDERSON.
